UNITED STATES PATENT OFFICE.

OSCAR E. OLSON, OF CHICAGO, ILLINOIS.

TOY SPECTACLES.

1,249,810.

Specification of Letters Patent. Patented Dec. 11, 1917.

Application filed August 8, 1917. Serial No. 185,014.

To all whom it may concern:

Be it known that I, OSCAR E. OLSON, a citizen of the United States, and a resident of the city of Chicago, county of Cook, and 5 State of Illinois, have invented certain new and useful Improvements in Toy Spectacles, of which the following is a specification.

My invention relates to a new and useful toy spectacle construction which will be of 10 durable and economical design, and which will be adapted to afford considerable amusement in use. Other objects will appear hereinafter.

The invention consists in the combinations 15 and arrangements of parts hereinafter described and claimed.

The invention will be best understood by reference to the accompanying drawings forming a part of this specification, and in 20 which,

Figure 1 is a front elevation of a toy spectacle construction embodying the invention, the same being shown in horizontal position or in a position such as is assumed 25 by the parts when the head of the user is held erect,

Figs. 2 and 3, views similar to Fig. 1 showing the arrangement of the parts when the device is tilted in either direction,

Fig. 4, a rear elevation of the device,

Fig. 5, a section taken on line 5—5 of Fig. 4, and

Fig. 6, a front elevation of one of the guide members of the construction detached.

The preferred form of construction as 35 illustrated in the drawings comprises two circular body members 7 which are connected by a bridge or nose piece 8 whereby the device may be applied to the nose of a user, 40 as will be readily understood.

The members 7 are formed with horizontally elongated openings 9 of a form corresponding with the opening or slit of the human eye. At the rearward side of each 45 member 7 is provided a disk 10 having a channel 11 formed therein which registers with the corresponding opening 9. The disks 10 are secured to the members 7 by means of turned back ears or lugs 12 formed upon the latter, ears or lugs 13 being formed 50 upon the members 10 which close the ends of channels 11.

Mounted in each of the channels 11 is a disk 14 designed and colored to correspond 55 with the pupil and iris of the human eye. The disks 14 are arranged, as seen, for exposure

at the openings 9, the arrangement being such that said disks are freely slidable or shiftable relative to said openings, this relative shifting of the disks 14 having the appearance of shifting of the eyes or gaze of the user. Said disks 14 will be comparatively heavy so as to permit of the ready shifting of the same upon tilting of the device, the shifting of said members being 60 illustrated in Figs. 2 and 3. The arrangement is such that the guide channels 11 are inclined slightly toward each other when the device is held horizontal, or the head of the user erect, in which position the members 14 will be positioned at the inner terminals of said guide channels as seen in Fig. 1. With this arrangement, then, it will be seen that the user of the device may effect apparent shifting of the eyes or gaze by 65 simply tilting the head from side to side. The effect of this movement of the members 14 is very amusing.

While I have illustrated and described the preferred form of construction for carrying 70 my invention into effect, this is capable of variation and modification without departing from the spirit of the invention. I, therefore, do not wish to be limited to the precise details of construction set forth, but 75 desire to avail myself of such variations and modifications as come within the scope of the appended claims.

Having described my invention what I claim as new and desire to secure by Letters Patent is:

1. A toy spectacle construction comprising a pair of members operatively connected together, said members having openings therein; and shiftably mounted elements arranged for exposure at said openings, substantially as described.

2. A toy spectacle construction comprising a pair of members operatively connected together, said members having openings therein; shiftably mounted elements arranged for exposure at said openings; and means for guiding said elements in the shifting thereof, substantially as described.

3. A toy spectacle construction comprising a pair of members operatively connected together, said members having openings therein; guide chambers provided at the rearward sides of said members; and shiftably mounted elements arranged in said chambers for exposure at said openings, substantially as described.

4. A toy spectacle construction comprising a pair of members operatively connected together, said members having openings therein; and shiftably mounted disks provided at the rearward sides of said members for exposure at said openings, substantially as described.
5. A toy spectacle construction comprising a pair of members operatively connected together, said members having openings therein; comparatively shallow guide chambers provided at the rearward sides of said members; and elements loosely mounted in said chambers for exposure at said openings, substantially as described.
6. A toy spectacle construction comprising a pair of members operatively connected together, said members having openings therein; comparatively shallow guide chambers provided at the rearward sides of said members; and comparatively thin disks slidably mounted in said chambers for exposure at said openings, substantially as described.
7. A toy spectacle construction comprising a pair of members operatively connected together, said members having openings

therein; shiftably mounted elements arranged for exposure at said openings; and means for guiding said elements in the shifting thereof, the guiding means coöperating with said members being normally inclined toward each other whereby said elements normally assume, by gravity, positions at the adjacent ends of said guides, when the device is held horizontal, substantially as described.

8. A toy spectacle construction comprising two spaced circular members having openings horizontally elongated; a bridge connecting said members; channeled guides at the rearward sides of said members registering with said openings; and disks slidably mounted in said guides for exposure at said openings, substantially as described.

In testimony whereof I have signed my name to this specification in the presence of two subscribing witnesses.

OSCAR E. OLSON.
